UNITED STATES PATENT OFFICE.

JOSEPH MASSOLLE, OF GRUNEWALD, HANS VOGT, OF BERLIN-SCHONEBERG, AND JOSEF ENGL, OF GRUNEWALD, GERMANY, ASSIGNORS TO TRI-ERGON LIMITED, OF ZURICH, SWITZERLAND.

ARRANGEMENT FOR ACOUSTIC CINEMATOGRAPHY.

Application filed April 4, 1921. Serial No. 458,629.

To all whom it may concern:

Be it known that we, JOSEPH MASSOLLE, HANS VOGT, and JOSEF ENGL, citizens of the German Republic, residing at Grunewald, Berlin-Schoneberg, Grunewald, Germany, respectively, have invented certain new and useful Improvements in Arrangements for Acoustic Cinematography (for which we have filed an application in Germany July 10 25, 1919), of which the following is a specification.

In acoustic cinematography the optical operation is photographically recorded upon a film in parallel with the acoustical operation in order to ensure synchronism. For the reproduction, positives made from these negative records are converted by means of photoelectric cells into microcurrents of acoustic characteristics; that is to say, light 20 is passed through the positive sound record on the film, and falls on the cell, which produces the currents. For recording, the current produced by a microphone is fed to a recording lamp, the varying illumination of 25 which produces a photographic record upon the negative film. The microphone, in recording, and the photo-electric cell in reproducing, each constitute a means for producing an acoustically-modulated current.

These known arrangements have however important disadvantages. In particular the microcurrents (of the order of magnitude 10^{-6} to 10^{-4} amperes), are not sufficient to uniformly reproduce with sufficient volume the 30 sounds produced by them in a room of considerable size. The use of low frequency amplifiers has the disadvantage that in accordance with prior practice low frequency transformers have to be used as a coupling 35 means which in consequence of magnetic hysteresis, undesirable resonance positions and the capability of taking up disturbing low frequency alternating fields, cause falsification of the speech and of its tone colour 40 and intensify further also all disturbing noises. Very strong electro-magnetic disturbing fields manifest themselves in cinematographic apparatus, the inductive action of which is especially marked on the amplifier circuits of the acoustic apparatus, if 45 the use of amplifiers in the latter is attempted. These disturbing effects are produced, for example, by the projection arc lamp of the moving picture projecting ma-

chine, (closely adjacent to the acoustic apparatus), by the motor for the projecting machine, by the electric lamps by which the stage is lighted in recording, etc. These cause the disturbing effects on the low frequency transformers, as noted above. 55

In consequence hereof these methods of intensification have hitherto not obtained any practical importance. The effect of the synchronism between the optical and acoustical operation may be annulled by a distorted reproduction of the speech or other sounds, particularly when an amplification of this speech or sound and with it an augmentation of its distortion is necessary. 60

This invention has for its object an arrangement which enables amplification to be produced free from distortion without the above described disadvantages. This arrangement avoids all the hitherto customary agencies, which together with sources of disturbance, such as those mentioned prevent the distortion free recording and reproduction of the acoustic operations. 70

The invention consists accordingly in the use, (in acoustic recording and reproducing systems embodying amplifiers, which systems are used in connection with moving picture recording and reproducing apparatus in which sources of disturbance are present, such for example, as those mentioned), of coupling means for various of the elements of the acoustic system, by which the effect of such disturbances on the amplifier circuits will be prevented. 80

The arrangement consists in the combination of the recording and reproducing means, (microphone, photo cells, telephone, etc.) with amplifiers (vacuum tubes) which possess no inertia, and whose elements are galvanically coupled, i. e. resistance-coupled, 90 without the use of low frequency transformers. The arrangement may also be carried out in such a manner that for the purpose of influencing high frequency currents by acoustic currents high frequency amplifiers without inertia are used with iron free high frequency transformers as coupling means therefor. These high-frequency transformers are relatively insensitive to disturbance by low-frequency magnetic fields, such as those produced by the sources of disturbance mentioned. In this arrangement a high frequency alternating current of con- 95 100 105

stant frequency is transmitted from one amplifying tube to the next, the amplitudes thereof being of various magnitudes according to the acoustic influence; that is to say, high frequency current from a suitable alternating current source is fed into the system, and this is modulated acoustically.

The disturbances and distortions which are caused by low frequency transformers are consequently avoided in the new arrangement. In the present application the species of invention first referred to, involving the use of the resistance couplings, will not be specifically claimed, the same being covered in a divisional application, Serial No. 746,741 filed Oct. 29, 1924. The freedom from disturbance can in the second form of arrangement described also be further increased by the use of resonance circuits.

The invention is exemplified in the appended drawings, in which Fig. 1 represents diagrammatically a system for simultaneously recording, on a moving film, pictures and the accompanying sounds, the resistance coupling form of the invention being shown; and Fig. 2 represents diagrammatically a system for reproducing, from a moving film, pictures and the accompanying sounds, the high frequency transformer coupling form of the invention being illustrated.

In Fig. 1 a pair of thermionic amplifiers are indicated as resistance-coupled in a system for recording sound on a moving film. The film is indicated diagrammatically at 1, the moving pictures being produced on the film by the usual means indicated diagrammatically by the projecting lenses 2 of the moving picture apparatus 3, pictures thus being made for example of actors upon a stage 4 illuminated in the usual way by arc lamps, which are indicated at 5—5.

The speech or other sounds produced by the actors or accompanying their action fall upon a microphone indicated diagrammatically at 6. A current is accordingly produced in the circuit 7, leading from the microphone, which current is sound-modulated, that is it fluctuates in correspondence with the sound producing the same. This circuit 50 leads to a thermionic amplifier 8, one side of the circuit being connected to the usual filament 9 of the amplifier and the other side to the grid 10, in the usual manner.

Amplified current flows from the plate 11 of amplifier 8 to the grid 10¹ of a second amplifier 8¹, it being understood that as many amplifiers are used in this system as is found desirable. From the last amplifier of the series, illustrated as the amplifier 8¹, an output circuit 12 is indicated as leading to a recording lamp indicated diagrammatically at 13. The illumination of this lamp is varied in accordance with the sound modulated current received thereby and the light thus varied falls upon the film 1 to make a

negative record corresponding to the sound as is well-known. The amplifiers of the system are coupled together by resistances, resistance 15 being indicated as connected across the output circuit of amplifier 8 in the well-known manner. Similarly the microphone 6 is illustrated as resistance coupled to the first amplifier 8, resistance 15^a being shown as connected across the circuit leading from the microphone to the filament and grid of the tube 8. Batteries, 16, 16^a and 16^b are conventionally indicated as included in the circuits 7, 17 between the amplifiers, and 12 extending between amplifier 8¹ and the recording lamp 13, this being, of course, common practice. A resistance 15^b is also indicated as included in the circuit 12 leading from the last amplifier. Condensers 18 and 18^a are indicated in the grid leads of amplifiers 8 and 8¹, merely by way of example. It may be noted that coupling resistance 15^a for the microphone corresponds to the resistance described in our copending application Serial No. 458,632, entitled Method for the control of electric currents by power of sounds, filed April 4, 1921, and there stated to be the coupling resistance of the microphone for amplifying or intensifying tubes.

In Fig. 2, illustrating the high frequency transformer coupling form of the invention, the invention is indicated by way of example as applied to a sound reproducing system accompanying moving picture projection apparatus.

In Fig. 2 the film 1^a, bearing the pictures, and also the sound record, is fed past the projection lamp 19, which may be a powerful arc lamp, the light from which passes through the picture record on the film and is projected on screen 22 in the usual manner. This lamp is a source of considerable electro-magnetic disturbance for adjacent electrical apparatus, such as the acoustic apparatus close by.

Light from a source 23 passes through the sound record on the film and falls upon the photo-cell, such as the photo-electric cell 24. The circuit 25 leading from this cell connects to the vacuum tube amplifier 26, the anode 24^a of the cell being illustrated as connected to the grid 26^b of the tube, and the cathode 24^c of the cell to the filament 26^d of the tube. The output circuit of tube 26 is connected to the grid and filament of a second tube 28 by a high frequency, iron-free, air-core transformer coupling 29. As many tubes connected together by similar transformer couplings as are desired may be used. From the last tube appropriate connection as by transformer coupling 29¹ may be made to a suitable telephone or loud speaker (not shown). High frequency A. C. current may be introduced into the system from a suitable source for example by the transformer coupling indicated at 30,

The connections indicated are the usual ones for transformer-coupled amplifying apparatus. The transformer circuits may be tuned, if desired, by the use of suitable condensers (not shown), as is well-known, to produce the resonance circuits referred to. A resistance 27 is indicated as connected in the anode-cathode circuit of the photo-cell 24.

10 The species of invention involving the high frequency transformer couplings may, as stated, be used in a recording system as well as in a reproducing system, in which case a microphone would be used in place 15 of the photo-electric cell, as the means for producing the sound-modulated current, in the circuit leading to the first amplifier, and the last amplifier would lead to a recording lamp by which a photographic record is 20 made on the negative film. Similarly, the resistance coupling species of the invention may, of course, be used in the reproducing system.

We claim:

25 1. In acoustic-cinematographic apparatus, including an electric device adapted to cause electro-magnetic disturbances in adjacent electrical apparatus, the combination of means for producing an acoustically- 30 modulated electric current, thermionic amplifying means and coupling means between

various of said means constructed to prevent the disturbing effect of said device in the circuit of said amplifying means.

2. In acoustic-cinematographic apparatus, including an electric device adapted to cause electro-magnetic disturbances in adjacent electrical apparatus, the combination of means for producing an acoustically-modulated electric current, a plurality of 40 amplifying tubes, connections between said first named means and the first tube and coupling means between successive tubes comprising high-frequency air-core transformers, and connections for transmitting 45 high-frequency alternating current to the input circuit of said first tube.

3. In acoustic-cinematographic apparatus, including an electric device adapted to cause electro-magnetic disturbances in 50 adjacent electrical apparatus, the combination of means for producing an acoustically-modulated electric current, thermionic amplifying means and coupling means between all of said means constructed to 55 prevent the disturbing effect of said device in the circuit of said amplifying means.

In testimony whereof we affix our signatures.

JOSEPH MASSOLLE.

HANS VOGT.

DR. JOSEF ENGL.
